UNITED STATES PATENT OFFICE

101,669

DESIGN FOR A RADIATOR COVER

Ned Glassberg, New York, N. Y.

Application September 11, 1936, Serial No. 64,802

Term of patent 3½ years

To all whom it may concern:

Be it known that I, Ned Glassberg, a citizen of the United States and a resident of the city of New York, county of Kings, and State of New York, have invented a new, original, and ornamental Design for a Radiator Cover, of which the following is a specification, reference being had to the accompanying drawing forming a part thereof.

Fig. 1 is a front elevational view of a radiator cover embodying my new design, in closed condition; and

Fig. 2 is a similar view thereof showing the

appearance of the radiator cover when the flaps are turned down.

The dominant feature of my design resides in the contrasting appearance of the vertical flaps with the body portion of the cover. The contrasting effect is due to the vertical stripes in the flaps and the horizontal stripes in the body portion as well as the flaps being of a color different from that of said body.

I claim:

The ornamental design for a radiator cover as shown and described.

NED GLASSBERG.
